SHOTGUN CARTRIDGE

Walter Edwards, Luton, England

Application February 13, 1937, Serial No. 125,634
In Great Britain February 14, 1936

5 Claims. (Cl. 102—15)

This invention relates to cartridges and more particularly to shot cartridges for breech loading sporting guns.

5 In a cartridge according to the specification of my prior United Kingdom Patent No. 389,211, a cup or shell containing shot is attached to a wad, the cup serving to retain the shot and prevent spreading thereof until it has travelled some distance from the muzzle of the gun.

10 The present invention has for its object to provide an improved cartridge whereby the shot shall be released to spread only after travelling a predetermined distance from a gun.

15 In a shot cartridge, according to the invention, the shot is contained within a cylindrical cup or shell the closed end of which is remote from the base or head of the cartridge and is formed with one or more apertures.

20 Preferably a thin disc fitting freely within the cup or shell is located between the apertured end thereof and shot contained therein.

25 Preferably also, the side wall of the cup or shell is slotted longitudinally from the rim of the latter. The "cylindrical" wall or part thereof of the cup or shell may be ribbed or corrugated.

30 Of the accompanying drawing, Figure 1 shows in part-sectional elevation a cartridge according to one form of the invention, Figures 2, 3, 4 and 5 being end views of typical alternative forms of a part of the cartridge; Figure 6 shows the part of Figure 5 in sectional elevation on the line 6—6 of that figure, whilst Figure 7 is a fragmentary sectional plan view on the line 7—7 of Figure 6.

35 As shown in Figure 1, a cartridge has the usual outer paper or brass case 11 and metal percussion cap 12 and contains the usual powder charge and wads 13 of felt, card, cork or the like. The shot indicated at 14, however, is contained within a cup or shell 15 of metal foil the closed end 16 of which is remote from the base or head of the cartridge and is formed with apertures 17 and dished as shown. A thin metal disc 18 which fits freely within the cup or shell 15 is located between the apertured end 16 of the cup or shell 15 and the shot 14 therein. As shown, the cup or shell 15 is secured within the outer case 11 in known manner by means of the usual cardboard wad 19 and inturned end 20 of said outer case 11. It is found in practice that after leaving a gun by which the cartridge is fired, the cup or shell 15 does not release the shot 14 to spread until it has travelled a considerable distance. It is also found that the extent of the opening at the end of the 55 cup or shell has some effect in determining the

distance from a gun at which the shot will be released from the cup or shell to spread, and there are shown in Figures 2, 3, 4 and 5 some typical examples of how these openings may be formed.

5 As shown in Figure 6, the side wall 21 of the cup or shell 22 is slotted longitudinally as indicated at 23, and is corrugated as clearly shown in Figure 7.

10 The cup or shell, which may be termed a "shot concentrator", of a cartridge according to the invention need not necessarily be formed from metal but may, for example, be formed from cardboard, or wound paper, or from a combination of such material and metal. Where the cup or shell 15 is corrugated, said corrugations need not extend completely over the outer wall thereof and may, if desired, be formed helically. Further the end of a cup or shell may be dished as shown and/or formed with one or more annular grooves or 20 corrugations.

15 Cartridges in accordance with the invention throw a great density of shot within a given area at a given distance from the gun, for example, one design of cup or concentrator will throw substantially all its shot within an area of thirty 25 inches diameter at a distance of forty-five yards from the gun, whilst another cup or concentrator may be such as to do the same at a distance of say fifty-five yards.

30 The cup or shell of a shot cartridge according to the invention may be designed to produce similar results over a greater distance than those just mentioned.

35 By employing shot concentrators as above described it is found that individual pellets retain their sphericity and are not subject to "balling", or barrel scrubbing to the extent which occurs with standard loose shot charges, and thus increased velocity and consequent increased striking energy may be obtained.

What I claim to be new is:

1. In a shot gun cartridge, an outer casing, a cylindrical shell therein, said shell being fully open at one end and apertured at the other end, 45 which latter end is located adjacent the mouth of the cartridge, and a disc within the shell, said disc fitting freely between the apertured end of the shell and shot within the shell, said disc and apertured end of the shell cooperating with the 50 shell for permitting the retention of the shot within the shell for a predetermined length of time after discharge from a gun.

2. In a shot gun cartridge having an outer casing and shot, a cylindrical shell within the casing, 55

said shell being fully open at one end and apertured at the other end, which other end is located adjacent the mouth of the cartridge, and a disc fitting freely within the shell and located between the apertured end thereof and the shot, said shell having a side wall formed with slots extending from the open end of the shell longitudinally thereof.

- 5 3. In a shot gun cartridge having shot therein, a cylindrical shell carrying the shot therein and within the cartridge, said cylindrical shell being fully open at one end and apertured at the other end, said apertured end being located adjacent the mouth of the cartridge, and a disc fitting freely within the shell and located between the opposite end thereof and the shot, said cylindrical shell having a wall formed with longitudinal corrugations.
- 10 4. In a shot gun cartridge, shot therein, a cylindrical shell within the cartridge and containing the shot and being fully open at one end and apertured at the other end, said latter end of the shell being located adjacent the mouth 5 of the cartridge, and a disc fitting freely within the shell and located therein between the apertured end and the shot, said apertured end of the shell comprising a substantially star-shaped aperture.
- 15 5. In a shot gun cartridge, shot therein, a cylindrical shell in the cartridge containing the shot and being fully open at its inner end and apertured at its outer end, and a disc fitting freely within the shell and located between the aperture and the shot, said apertured end of the shell being dished. 10 15

WALTER EDWARDS.
